UNITED STATES PATENT OFFICE.

ELLIS S. HELWITZ AND ARTHUR LOBEL, OF NEW YORK, N. Y.

SHOE-HEEL.

1,134,383.

Specification of Letters Patent.

Patented Apr. 6, 1915.

Application filed June 11, 1913. Serial No. 772,976.

To all whom it may concern:

Be it known that we, ELLIS S. HELWITZ and ARTHUR LOBEL, citizens of the United States, and residents of the borough of Brooklyn, county of Kings, city and State of New York, have invented certain new and useful Improvements in Shoe-Heels, of which the following is a description in such full, clear, and exact terms as will enable any person skilled in the art to which it pertains to make and use the same.

The invention relates to an improvement in rubber heels for shoes and the object of the invention is to provide a convenient and economical means of reversing or changing the position of the rubber heel so that as the same wears down a new surface may be presented.

To this end our invention consists of certain novel features of construction which will be fully set forth hereinafter and particularly pointed out in the claim.

Reference is now had to the accompanying drawings in which—

Figure 1 is a bottom view of one form of the invention, Fig. 2 is a section thereof on the line 2—2 of Fig. 1, Fig. 3 is a bottom view of another form of the invention, Fig. 4 is a section thereof on the line 4—4 of Fig. 3, Fig. 5 is a bottom view of still another form of the invention, and Fig. 6 is a section on the line 6—6 of Fig. 1.

Our invention may be made in various forms of construction and we are not limited to the precise forms here shown. These forms, however, do represent the preferred constructions and are thought to be suitable for all occasions.

Referring to Figs. 1 and 2, the rubber heel is formed in two sections *a* and *b* by cutting the heel on the curved line *c* so that the section *b* will be round. The part *a* is nailed to the heel of the shoe as indicated at *a*¹ and the part *b* is furnished with a metal disk *b*¹ embedded in the rubber to carry a screw *d* which extends into the leather heel and thereby mounts the part *b* so that by loosening the screw *d* said part may be freely turned. In this way when one side of the

heel wears down the part *b* may be given a turn and a new surface presented. For keeping the corners *a*² of the part *a* snugly in position against the part *b* we employ springs *e* which are embedded in the rubber points and serve to press said points inward toward each other.

In Figs. 3 and 4 the construction above described is followed excepting that the points *a*³ of the section *a* are not furnished with springs to hold them in place but are rounded off as shown in Fig. 1.

According to the construction shown in Fig. 5 the parts *a* and *b* are provided as before, but the incision is not made clear through the heel but only partly through the heel leaving an extension *a*⁴ of the part *a* projecting over the rotating part *b*. In this case the fastenings *a*¹ are put through not merely the part *a* proper, but also through the part *a*⁴ of the part *a*. Where they may be required the springs *e* may or may not be employed in the construction shown in Fig. 5, all of which must be in accordance with the desire of the manufacturer or user.

It will be seen that in all of the forms of my invention the distinct advantages provided allow the part *b* of the heel to be rotated so as to turn a new section into position whenever the heel is worn down. This will increase the life of the heel anywhere from four to six times the life of a heel of ordinary construction and the construction which we provide involves the use of no more material than the old construction. To adjust the heel it is only necessary to loosen the screw *d* and turn the section *b* after which the screw may be tightened to hold the section in place.

Various other advantages of the invention will be apparent. It will also be apparent that various modifications may be made in the invention without departing from the principles hereinafter set forth.

Having thus described our invention what we claim, as new and desire to secure by Letters Patent of the United States is:—

A rubber heel for shoes having a stationary part of rubber and a part arranged to

turn, the stationary part having portions projecting therefrom and partially embracing the turning part and provided with springs embedded therein so constructed and arranged as to tend to press the projecting portions into contact with the turning part.

In testimony whereof we have hereunto

signed our names in the presence of two witnesses.

ELLIS S. HELWITZ.
ARTHUR LOBEL.
